COMBINED ELECTRICAL POWER CONNECTOR AND THERMOSTATIC CONTROL

Melvin H. Boldt, Glenview, Ill., assignor to National
Presto Industries, Inc., Eau Claire, Wis., a corporation
of Wisconsin

Application June 1, 1956, Serial No. 41,736

Term of patent 14 years

(Cl. D52—7)

Fig. 1

Fig. 2

Fig. 3

Fig. 4

Figure 1 is a top plan view of a combined electrical power connector and thermostatic control showing my new design;

Figure 2 is a side elevational view thereof;

Figure 3 is an end view thereof; and

Figure 4 is a view of its opposite end.

The dominant features of the design reside in the portions shown in full lines.

I claim:

The ornamental design for a combined electrical power

connector and thermostatic control, substantially as shown and described.
